CHARLES D. FAGAN, OF SHARON, PENNSYLVANIA, ASSIGNOR TO SHARPSVILLE BOILER WORKS CO., OF SHARPSVILLE, PENNSYLVANIA, A CORPORATION OF PENNSYLVANIA.

FLOW INDICATOR.

Application filed July 28, 1927. Serial No. 209,153.

The present invention relates to a fluid flow indicator and more especially to a device for indicating the flow of gasoline or the like for service stations.

5 In devices for public sale of gasoline at gasoline service stations, it is desirable to provide means to assure the purchaser that gasoline is flowing through the service line. The present invention is a visual indicator 10 for that purpose.

In the present invention, the indication of flow is accomplished by a rotating member driven by the flow of gasoline and arranged in a casing between a pair of windows in 15 such manner as to cause the gasoline flowing through the casing to become turbulent so that the liquid itself causes slight variations and the light passing through the said windows and an observer may easily and 20 quickly ascertain that flow is taking place. The more rapid the flow, the greater the disturbance.

It is realized that the present invention may be embodied in structures other than 25 those specifically disclosed herewith and therefore, this disclosure is to be understood as illustrative and not in the limiting sense.

Fig. 1 is an elevational view of a preferred form of the present invention with 30 a portion of the casing broken away to show the internal construction of the device.

Fig. 2 is a longitudinal sectional elevational view taken on line 2—2 of Fig. 3.

Fig. 3 is an end sectional elevation taken 35 on line 3—3 of Fig. 1 looking in the direction of the arrows.

Referring now to the drawings, which illustrate a preferred form of the invention, the device comprises a casting 1 comprising 40 the major portion of the casing. This casting comprises a substantially cylindrical body portion 2, which is provided with an inlet conduit 4 and an outlet conduit 5. The inlet conduit 4 terminates in a curved spout 6 having substantially a horizontal mouth 7, when the device is mounted for operation 45 in the preferred position. The outlet conduit 5 leads from the hollow interior of the body portion 2 and is adapted to carry away fluids coming in through the inlet conduit 4. A post 8 is cast integral with the body casting 1 and extends upwardly from the lower side wall of the inlet conduit 4 in such manner as to occupy a central position in the

circular opening at the mouth of the inlet 55 conduit. This post 8 is provided with a guide opening 9 the axis of which is parallel to the axis of the outlet opening at the mouth 7 of the inlet curved spout 6. An adjustable bearing 10 comprises a screw 60 threaded member passing through a screw threaded opening in the upper central part of the body 2 and secured in locked position by a lock nut 11. This adjustable bearing member 10 is provided with a bearing opening 12 directly above and on the same axis as the guide opening 9 in the post 8. A rotor 14 comprising a sheet metal fan is mounted upon a rotor shaft 15, the lower end of which rests in the guide opening 9 70 and the upper end of which rests in the bearing 12. The distance between the upper end of the bearing opening 12 and the bottom of the guide opening 9 is greater than the total length of the rotor shaft 15 so that 75 when liquid comes in through the inlet conduit 4 and strikes the blades of the rotor 14, the rotor and its shaft 15 are raised in such manner that the shaft bears only at its upper end against the adjustable bearing 10, 80 the opening 9 in the post 8 merely acting as a guide to prevent the rotor and its shaft being displaced or carried away by the flow of the liquid, and the upper end of the shaft taking the thrust during the flow of liquid 85 through the device. The sides of the cylindrical body portion 2 preferably are turned to provide sealing faces. These sealing faces are provided with sealing grooves 16 and with flat sealing zones 17. Compressible 90 seals 13 such as cork rings or the like are adapted to overlay the sealing faces and to support circular glass windows 18, one on each side of the device. Compression gaskets 19 also of cork or other material, are inserted between the glass windows 18 and sealing rings 20. The sealing rings are provided with ears 21 through which pressure screws 22 pass into anchor ribs 24 on the cylindrical body 2. As the pressure screws 100 22 are tightened, pressure is transmitted through the sealing rings, the compression gaskets, to the glass windows and then to the sealing gaskets extending over the sealing grooves 16 and the sealing zone 17 on 105 the sealing faces. This pressure tends to drive the rings into the sealing grooves and thereby form intimate and secure seals.

which prevent the leakage of liquid from under the glass windows. The device is preferably mounted as indicated in Fig. 1 with the shaft 15 of the rotor 14 substantially vertical, and since there are windows on both sides of the device, the rotor is clearly visible. The device is preferably mounted beyond the meter, and in the service line so that any liquid passing through the device must necessarily pass into and out of the service line, and in order that there may be no mistake in properly mounting the device, the inlet connection for the conduit 4 is provided with an indicating arrow 25.

15 When the device is connected as indicated, fluid coming into the device through the inlet conduit 4 flows out of the mouth 7 thereof and into the hollow cylindrical space surrounding this outlet 7, which is located in substantially the mid portion of the cylindrical body 2. The flow is in all directions as indicated by the arrows A in Fig. 2 and the moving liquid strikes the vanes on the rotor 14, thereby immediately lifting the 20 rotor from normal position, indicated by the dotted line X in Fig. 1, to operative position, indicated by dotted line Y. When in operative position, the flow of the liquid causes the rotor to rotate rapidly and as the 25 vanes turn on the axis of the shaft, they produce a fluttering effect which is very noticeable and furthermore, the flow of the gasoline as it leaves the mouth of the inlet conduit, and turns in both directions as it is thrown out by the rotor and as the flow conforms to the cylindrical body, produces striations which show quite a different appearance through the windows than when the liquid in the casing is quiescent and no flow 30 is taking place.

40 In devices of this character, it is particularly desirable that the mechanism shall be as simple as possible and require minimum amount of attention. In rotating devices, the difficulties usually arise with the bearings. In the present case, the rotor substantially floats so that there is a minimum of friction between the shaft and its supports. The axially aligned openings are considerably larger than the shaft so that side contact of the shaft therewith is slight and is merely sufficient to maintain the shaft in position. The main bearing, being at the top of the shaft, sustains but little pressure 45 when the rotor is raised because the weight of the rotor and shaft tends to partly overcome the lifting force due to the flow. In view of the fact that as soon as the flow is stopped, the rotor drops to its normal position of rest and the end of the shaft leaves the thrust bearing, this permits any particles of metal that are worn away or any grit which might accidentally lodge in the bearing to drop out and be washed out of the 50 bearing by the flow of liquid, so that the

main working bearing of the device is so frequently cleaned as to be substantially clear of foreign matter at all times.

Having described my invention, I claim:

1. A flow indicator comprising a cylindrical chamber, an inlet conduit terminating in the center of the cylindrical chamber in a vertically directed outlet opening, an outlet conduit leading from said cylindrical chamber, a pair of windows on said cylindrical chamber, and a rotor mounted over the mouth of the inlet conduit and visible through said windows, said rotor being adapted to be rotated by flow of liquid from the mouth of said inlet conduit. 70

2. A flow indicator comprising a cylindrical chamber, an inlet conduit terminating in the center of the cylindrical chamber in a vertically directed outlet opening, an outlet conduit leading from said cylindrical chamber, a pair of windows on said cylindrical chamber, a rotor mounted over the mouth of the inlet conduit and visible through said windows, said rotor being adapted to be rotated by flow of liquid from the mouth of said inlet conduit, and an indicator on said inlet conduit to indicate the mounting of said device to obtain proper direction of liquid through the device. 80

3. A flow indicator comprising a central chamber, a window on each side of said central chamber, an inlet conduit having the mouth thereof constructed to deliver an upwardly flowing stream of liquid into said chamber, an outlet conduit leading from said chamber, a rotatable shaft, a rotatable indicator mounted on said shaft and over said outlet conduit, said indicator and shaft being permitted a limited vertical movement, a bearing above said indicator and against which the shaft of the indicator is adapted to be raised when said indicator is rotating, and means to guide the lower end of said shaft. 90

4. A flow indicator comprising a cylindrical central chamber having a substantially horizontal axis, a window on each side of said chamber to permit a clear vision through said chamber, an inlet conduit leading to said chamber and being adapted to deliver liquid in substantially a vertical direction into the mid portion of said chamber, an outlet conduit leading from the lower portion of said chamber, the arrangement of the inlet conduit and the outlet conduit being such as to cause the liquid in such chamber to take a varied path therethrough whereby the variation in density in said liquid produces an optical effect upon light passing through said windows so that the observer can determine whether there is a flow of liquid through said chamber or whether said liquid is not flowing therethrough. 110

5. A flow indicator comprising a cylindrical chamber having substantially a horizon- 120

tal axis, a window on each side of said chamber to permit a clear vision therethrough, an inlet terminating in a vertically directed mouth located at substantially the axis of said chamber, a rotatable indicator mounted above the mouth of the inlet conduit, a shaft for said indicator, guiding means for the lower end of said shaft, another guiding means for the upper end of said shaft, a thrust bearing arranged relative to both guiding means to permit said shaft to be raised and lowered into and out of contact with said bearing to permit the automatic cleaning of said bearing during the operation of said device.

6. A flow indicator comprising a substantially cylindrical chamber having substantially a horizontal axis, a window on each

side of said chamber to permit a clear vision through the chamber, an inlet member comprising a conduit terminating in the central portion of said chamber and with an upwardly directed mouth to direct liquid against the upper curved wall of the chamber, and an outlet conduit located at the lower side of said chamber with the mouth of said outlet conduit being substantially coincident with the side wall of said chamber, whereby liquid coming in through said inlet conduit is stirred up so as to produce an optical effect upon light passing through said windows to enable an observer to determine when liquid is flowing through said chamber.

CHARLES D. FAGAN.
